UNITED STATES PATENT OFFICE

2,468,943

PRESSURE FLUID SERVOMOTOR

John B. Parsons, Toledo, Ohio

Application May 18, 1945, Serial No. 594,577

3 Claims. (Cl. 121—44)

1.

This invention relates to regulator mechanism for windows of vehicles such, for example, as automobiles, in which the window is mounted for swinging movement, but more particularly to ventilating wings or vanes such as are mounted on automobile doors on an up and down axis to swing between open and closed positions so as either to deflect air inside of the automobile or to withdraw air from the inside of the automobile, and an object is to produce new and improved mechanism for automatically actuating windows of the above type, the same constituting an improvement on the structure shown and described in my Patent 2,338,965 dated January 11, 1944, and entitled "Operating mechanism for ventilating wings," to the end that the structure may be manufactured more easily, the parts being adapted for more efficient assembly, the structure as a whole being more sturdy, positive and reliable in performance.

Other objects and advantages of the invention will hereinafter appear and for purposes of illustration but not of limitation, an embodiment of the invention is shown on the accompanying drawings in which:

Figure 1 is a fragmentary side elevation of the front end portion of an automobile showing the ventilating wing parts being broken away to show the regulator mechanism and the pump and connections being diagrammatically illustrated;

Figure 2 is a top plan view of the regulator mechanism indicating by broken lines the positions to which the ventilating vane or wing may be adjusted;

Figure 3 is an enlarged vertical sectional elevation of the regulator and its associated electro-magnetically controlled valve;

Figure 4 is a transverse sectional view on the line 4—4 of Figure 3;

Figure 5 is a perspective view of the piston body portion; and

Figure 6 is an enlarged fragmentary sectional view of the piston assembly and associated spring, taken on the line 6—6 of Figure 4.

The illustrated embodiment of the invention comprises an automobile body 10 having a side door 11 provided with a window opening 12 in which the usual vertically movable window panel is mounted. Forwardly of the opening 12 and separated therefrom by a vertically disposed guide bar 13 is a ventilating wing or vane 14, which is pivoted to swing about an up and down axis, the upper pivot being indicated by the number 15 and the lower pivot being indicated by the number 16. Fixed to the vane 14 and depend-

ing from the pivot 16 is a flat-sided post 17 which extends between the sides of a yoke 18, a pin or bolt 19 extending through registered apertures in the post 17 and yoke 18 for holding the parts together. It will be manifest that by rotation of the yoke 18, the ventilating wing 14 may be swung about its axis, as indicated by the broken lines on Figure 2.

The yoke 18 forms a part of the regulator mechanism and as shown on Figure 3, is an integral part of the slotted stub shaft 20 into which the straight portion of a helical ribbon shaft 21 is securely positioned by a bolt 22. The gradual curve 23 of the helix is formed by twisting a flat, elongate steel ribbon to the desired contour, the ribbon being shown rectangular in cross section.

Fitting the helical ribbon shaft 21 is a piston 24, which is formed with a slotted central opening 25 conforming to the cross section of and having a sliding fit with the shaft 21 so that the piston can move longitudinally of the shaft 24. The piston 24 comprises a substantially rectangular plate or body portion 24a from the under side of which depend four integral shouldered pins 27. A rectangular resilient rubber packing disc 26 is apertured to fit over the pins 27 and retaining the rubber disc 26 in place is a rectangular metallic plate 28 which is also apertured to fit over the pins 27, the latter being upset or riveted over as indicated on Figure 6 to hold the rubber disc 26 and plate 28 in position. It will be observed that the slot 25 in the plate 24a is of hour glass shape in cross section and as shown in Figure 6, registering slots are formed in the disc 26 and plate 28. It should be noted that the rubber disc 26 is so constructed and arranged that it not only effects a liquid tight seal outwardly with the inner walls of the cylinder but also affords an effective liquid tight seal inwardly with the helical shaft or ribbon 21.

On the upper side of the body portion 24a of the piston 24 and at each corner thereof are upstanding integral fingers 27a, the outer surfaces of which are rounded. Approximately midway of the length of each finger on the inside thereof is formed an inwardly extending shoulder 27b, the same being formed by reducing the thickness of the metal of the finger projecting outwardly therefrom. It will be manifest that the piston 24 may be conveniently formed by die casting.

The piston 24 is longitudinally slidable in an elongate sheet metal housing 29 which is rectangular in cross section with the corners thereof rounded as indicated on Figure 4 and conforms

to the curvature of the outer surfaces of the fingers 27a. The fingers 27a militate against the piston binding within the housing, insure a smooth sliding movement and also provide a mounting and enclosure for one end portion of a coil spring 30.

Manifestly the piston 24 is held against rotative movement but sliding movement thereof longitudinally of the elongate housing 29 is permitted. As a consequence, the longitudinal sliding movement of the piston 24 imparts rotative movement to the helical shaft 21 due to the cooperative engagement of these parts.

As will hereinafter more fully appear, fluid under pressure, such as a liquid, is introduced into the lower portion of the housing 29, thereby causing the piston 24 to travel upwardly within the housing 29 and impart rotational movement to the shaft 21 in one direction. It will be manifest that downward movement of the piston 24 causes rotational movement of the shaft 21 in the opposite direction. Such downward movement of the piston 24 is effected by the coil spring 30.

Integral with the stub shaft 20 and disposed a short distance below the yoke 18 is an annular collar 31 directly beneath which is another collar 32 of smaller diameter. The annular collars 31 and 32 are held between the cupped end plate 33 and a curved metallic plate 34 which acts as a bearing element and is backed by the end plate 33. The metallic end plate 33 serves to close the upper end of the elongate housing 29 and is securely positioned by fitting into the groove formed by crimping the upper end of the metallic housing 29 over the end plate 33. The upper annular collar 31 rides between a packing 36, which also snugly embraces the stub shaft 20 and contacts the end plate 33, and a lower packing ring 37, which embraces the lower annular collar 32 and contacts the metallic plate 34. It will be apparent that the shouldered portion of the collar 31 co-operating with the metallic end plate 33 and plate 34 provides a thrust bearing for the shaft 20 and serves to retain the shaft in the desired position.

The lower portion of the casing 29 extends downwardly below the lower end of the shaft 21, and mounted therein is an electromagnetically controlled valve assembly 38, which includes a solenoid 39 within which is disposed a valve member 40 which is normally urged upwardly to its seat by a coil spring 41, a portion of the latter being disposed within a sleeve 42. The arrangement is such that upon energizing the solenoid coil 39, the valve member 40 is moved downwardly, tensioning the spring 41 and enabling the fluid under pressure to flow therethrough to the piston 24. When the solenoid coil 39 is de-energized, the coil spring 41 moves the valve to its seat, thereby trapping the fluid within the casing 29 and retaining the shaft 21 in its adjusted position. Thus upward movement of the piston 24 is effected by the introduction of the fluid under pressure to the casing 29.

When it is desired to effect movement of the vane 14 in the opposite direction, the solenoid coil is energized but the source of pressure fluid is inoperative, thereby enabling the coil spring 30 to force the piston 24 downwardly and effecting a reverse rotation of the shaft 21. Thus, it will be manifest that the valve 40 serves both as an inlet valve to admit fluid under pressure for actuating the piston in an upward direction and also as an outlet valve through which fluid is

expelled from the cylinder upon downward movement of the piston in response to the expanding force of the coil spring. A still further advantage of the valve 40 is that it serves automatically to relieve pressure in excess of a predetermined maximum within the cylinder. Thus, in the event of expansion of the pressure fluid within the cylinder and beneath the piston, for example when the wing or vane is in closed position, the pressure so built up will unseat the valve 40, thereby relieving the pressure and militating against injury or damage to the regulator parts.

The extreme lower end of the casing 29 is closed by an end plate 43, which is held in place by crimping the end 44 of the casing 29 about the end plate 43, which at its inner section seats onto a shoulder in the sleeve 42. The sleeve 42 is drilled for fluid passage and pipe connections 45.

Detailed description of the source of pressure fluid is not considered necessary. Suffice it to say that a motor pump unit 46 containing its own fluid reservoir forces fluid such as oil under pressure through a tube 47 to the sleeve 42, the tube 47 also serving as a return line to enable fluid from the casing 29 to return to the reservoir. A switch 48 is indicated, one lead 49 therefrom extending to the solenoid coil 39, another lead 50 extending to a relay for controlling the unit 46, and a third lead 51 extending to a battery B or source of electrical current. The switch may assume the form as shown and described in my Patent 2,844,452, dated March 14, 1944, and is such that either the solenoid 39 may be energized alone, or the solenoid 39 and the pump unit 46 simultaneously may be operated, depending on the manner in which the switch 48 is actuated.

It is to be understood that numerous changes in details of construction, arrangement and operation may be effected without departing from the spirit of the invention especially as defined in the appended claims.

What I claim is:

1. A fluid pressure servo-motor comprising an elongate casing rectangular in cross section with the corner portions thereof rounded, a piston conforming substantially to the cross section of said casing and mounted therein for reciprocatory movements, said piston comprising a body portion shaped to fit within said casing, fingers extending from the corners of said body portion with the outer surfaces thereof rounded to conform to the rounded corners of said casing, pins projecting from the opposite side of said body portion, a resilient rubber disc apertured to fit said pins, means to hold said disc in place against said piston body portion, a shaft adapted to be operatively connected at its outer end to the work and projecting inside of said casing, an elongate helical actuating element on said shaft for rotation therewith, said piston having a slot fitting said actuating element whereby longitudinal movement of said piston imparts rotary movement to said shaft, a mounting within said casing for said shaft for holding same against axial movements, and means for effecting piston movement longitudinally of said casing.

2. A fluid pressure servo-motor comprising an elongate sheet metal casing rectangular in cross section with the corners thereof rounded, a piston conforming substantially to the cross section of said casing and mounted therein for reciprocatory movements, said piston having a body portion having a slot of hour glass shape in cross section, fingers rising from the corners of said

body portion respectively and shaped on the outside thereof to conform to the curvature of the corners of said casing, pins depending from said body portion, a resilient rubber disc having a slot registering with the slot in said body portion, and apertured to fit said pins, a plate having a slot registering with the slots in said body portion and disc and apertured to fit said pins, the outer ends of said pins being upset to hold the parts in place, a stub shaft mounted at one end of said casing and having a portion projecting outwardly thereof for connection to the window panel, and a yoke portion projecting inside of the casing, an elongate ribbon-like helical actuating element fitting said registering apertures in the piston body portion, disc and plate, means for clamping one end portion of said actuating element between said shaft yoke, a thrust bearing for said shaft, and a coil spring within said casing and having one end portion bearing against said piston body and disposed within said fingers.

3. A fluid pressure servo-motor comprising an elongate casing polygonal in cross section, a piston conforming substantially to the cross section of said casing and mounted therein for reciprocatory movements, a shaft adapted to be opera-

10
